VIRGIL E. TROUANT, OF WILKINSBURG, PENNSYLVANIA, ASSIGNOR TO WESTINGHOUSE ELECTRIC & MANUFACTURING COMPANY, A CORPORATION OF PENNSYLVANIA

RADIOTRANSMITTING SYSTEM

Application filed October 8, 1927. Serial No. 224,869.

My invention relates to radio transmitting systems, and it has particular relation to systems of the type in which the radiated power is maintained substantially constant while the frequency thereof is varied in order to transmit signals.

In the majority of radio-transmitting systems designed for telephonic communication, the signal is impressed on a constant-frequency carrier-wave as a modulation of the amplitude thereof. As an alternative, it has been proposed to alter the frequency of the carrier-wave in accordance with voice or other sounds and to thus transmit the signal as frequency-modulation rather than as amplitude modulation. Systems of the latter type have not given very satisfactory results in the past because of the many difficulties encountered when an attempt was made to shift the tuning of the frequency-determining circuits associated with the transmitting apparatus at a rate sufficiently rapid to follow the tones of the human voice or the notes of the musical scale.

In my copending application, Serial No. 199,677, filed June 18, 1927, I have disclosed certain methods whereby the frequency of radiated oscillatory-energy may be advantageously modulated by voice or other signals by directly varying the frequency of the oscillations generated by a piezo-electric crystal-controlled master-oscillator. The present invention is akin to the invention disclosed in my copending application and is in the nature of an improvement thereon.

One object of my invention is to provide appropriate means and circuit connections whereby the carrier wave of a radio transmitting system may be modulated, as to frequency, in a smooth, continuous manner, eliminating the abrupt changes incident to frequency-modulation systems known to the prior art.

Another object of my invention is to provide a modulating system that is equally effective for both voice and telegraphic signal transmission.

Another object of my invention is to provide a modulating system in which the frequency of a piezo-electric crystal-controlled

master-oscillator may be varied in accordance with audio or other signals without the expenditure of any considerable amount of power.

Still another object of my invention is to provide a modulating system that shall be substantially without time-lag in its response to signal impulses impressed thereon, rendering it particularly useful in picture transmission and the like.

According to my invention, the frequency of the oscillations generated by a piezo-electric crystal-controlled master-oscillator is caused, by the action of certain agencies later to be described in detail, to shift above or below the natural frequency of the crystal proper, the amount of the frequency-shift being proportional to the amplitude of the signal impressed on the system, and the rate at which the shift takes place being controlled by the frequencies involved in the signal.

In general, piezo-electric crystal-controlled oscillation-generators comprise a thermionic device having an input, or grid, circuit including the crystal, and an oscillatory output, or plate, circuit which is tuned to a frequency approximating the natural frequency of the crystal section. The thermionic device is maintained in the oscillating state by reason of the transfer of energy from the output circuit to the input circuit through the inter-electrode capacity of the device. The frequency of the oscillations is largely determined by the natural frequency of the crystal, the spacing of the supporting electrodes therefrom, the constants of the grid, or input, circuit and, as I have discovered, by the constants of the output, or plate, circuit. In other words, the oscillation frequency can, within definite limits, be forced to follow the tuning of the output circuit, provided the said circuit is not very greatly de-tuned in either direction from the state corresponding to the fixed tuning of the grid, or input circuit.

I am not prepared, at this time, to state the exact theory underlying my invention, but it is possible that the shift in oscillation frequency is caused by a change in the phase of the energy fed back to the input circuit from

the output circuit of the device. As is well known to those skilled in the art, in order to maintain oscillations in a network comprising a thermionic tube, at any given frequency, solely by reason of energy feed-back through tube-capacity, it is necessary that the output circuit have an inductive reactance to currents at the frequency in question. Should the output circuit be capacitive in reactance, 10 the phase of the feed-back is incorrect for the maintenance of oscillations, and it might be said that the system would, in that event, be "degenerative" rather than "regenerative." For this reason, it is highly probable that the 15 de-phasing of the feed-back energy, within certain small limits, is instrumental to some extent in altering, by small amounts, the oscillation frequency.

In a preferred embodiment of my invention, 20 the slight shift in the tuning of the output circuit of a thermionic oscillation generator is accomplished by connecting a reactive network in shunt to the oscillatory, or frequency-determining, circuit comprised therein, and by altering the effective value of the network in response to signalling frequencies. The grid circuit of the thermionic device preferably includes a piezo-electric crystal mechanically resonant to the desired mean 25 oscillation frequency, though I have, instead, utilized tuning-fork control with surprisingly good results. The changes in the reactance of the network may, if desired, be restricted to variations above a certain normal value, or may be restricted to variations below the normal value.

In order to effectively control the value of the reactance network associated with the output circuit of the thermionic oscillator, I have 30 found it practical to connect the plate-filament path of a second thermionic device in shunt to a portion thereof, and to change the resistance of the path by impressing signal-energy on the grid of the device. In this manner, by suitably proportioning the permanent direct-current bias potential applied to the grid of the thermionic device, herein-after termed the "shifter-tube," the reactance 35 changes in the network may be restricted to positive values, to negative values, or to both in combination, depending upon the type of signal it is desired to transmit.

The novel features which I consider characteristic of my invention are set forth with particularity in the appended claims. The invention, in its generic aspect, however, both as to its organization and its method of operation, together with further objects and advantages thereof, will best be understood by reference to the following description, taken in connection with the accompanying drawing.

The single figure of the drawing is a schematic view of the circuits and apparatus of a

radio transmitting system comprising a preferred embodiment of my invention.

Referring specifically to the drawing, a thermionic oscillator device 1, having the usual filament 2, plate 3 and grid 4, is provided with a grid, or input, circuit comprising a piezo-electric crystal section 5 supported between electrodes 6 and 7 which are connected to the grid and filament, respectively. A choke coil 8 and a biasing battery 10 are connected across the electrodes and together serve to maintain the grid at the best operating potential.

The plate, or output, circuit comprises an inductor 11 having a variable condenser 12 connected in shunt thereto, and includes a source 13 of plate potential. A by-pass condenser 14 is connected across the plate-potential source to provide a path for the radio-frequency component of the plate current.

Connections 15 and 16 extend from appropriate points on the inductor 11 to a frequency-changing device 17 which is arranged to select and amplify an appropriate harmonic of the natural crystal-frequency, and the amplified harmonic frequency is impressed on the input circuit of an amplifying device 18 tuned thereto.

The output of the amplifying device is impressed on the input circuit of a power-amplifier 20, preferably comprising a plurality of high-power, water-cooled thermionic devices (not shown), from which energy at the harmonic-frequency is normally supplied through a variable coupling device 21, to a radiating structure comprising an antenna 22, a variable reactor 23 and a counterpoise 24.

The counterpoise may be replaced by a ground connection, if desired, in which event, the coupling reactor could advantageously be replaced by a coupling transformer having its primary winding included in the output circuit of the power amplifier and its secondary winding included serially in the antenna-ground structure as shown in the Reissue Patent to Heising 14,967.

The frequency changer 17 is not an essential element of the system, it being feasible to directly amplify and radiate the frequency generated by the crystal-controlled oscillation generator. It has been found, however, that crystal sections so dimensioned as to oscillate at frequencies corresponding to the extremely short wave-lengths now being utilized for long distance transmissions are quite prone to breakage during use. For that reason, it is preferably to utilize a crystal oscillating at a low frequency and to select, for transmission, one of the higher harmonics of the oscillation frequency.

The fundamental frequency generated by the local oscillator may be conveyed by radio or over wire lines to additional radio transmitters and there directly amplified and radiated, or there passed through appropriate

frequency changers before amplification and radiation. In addition, harmonic frequencies other than the frequency utilized for radiation from the station at which the illustrated apparatus is situated, may also be conveyed to distantly located radio transmitting stations and there either amplified and radiated or changed in frequency before radiation. In either event, the modulation impressed on the fundamental frequency, in the manner later to be described in detail, appears as a modulation of any harmonic utilized for transmission or radiation, being represented by a shifting of the frequency of said harmonic toward and away from the normal frequency thereof.

In order that the oscillations generated by the oscillator device 1 may be modulated by signal-frequencies, I provide a plurality of 20 "shifter-tubes," 25 and 26, each of which may be a thermionic device of the usual type having a filament 27, a grid 28 and a plate 30. Similar elements of the shifter-tubes are connected in parallel, and the filaments thereof 25 are supplied with power from a common source 31. If desirable, the plurality of tubes illustrated may be replaced by a single tube capable of handling an equivalent amount of power.

30 The common input circuit of the shifter-tubes comprises the secondary 32 of an audio-frequency transformer 33, the primary 34 of which may be energized from a microphone 35 or may be included in the output 35 circuit of an amplifying device (not shown).

The plate circuit of the shifter-tubes may be traced from the plates 30 over a conductor 36, through a portion of an inductor 37, through a portion of the plate-potential 40 source 13, to a conductor 38 which is common to the filament circuits of the shifter-tubes and the oscillator tube 1. The end of the inductor 37 opposite the end which is connected to the voltage source 13 is coupled to 45 the plate of the oscillator-tube through a stopping condenser 39, and a by-pass condenser 41 is connected in shunt to the portion of the voltage source 13 that supplies plate potential to the shifter-tubes.

50 The inductor 37 and the stopping condenser 39 accordingly constitute a reactive network connected across a portion of the output-circuit of the oscillator-tube and together influence, to some extent, the tuning 55 of the said circuit.

In the operation of a system arranged according to my invention, the output circuit of the oscillator-tube is preferably tuned to approximately the natural frequency of the 60 piezo-electric crystal section, and oscillations are accordingly maintained therein by reason of the feeding-back of energy from the plate-circuit to the input circuit through the capacity existing between the plate and grid electrodes.

Any alteration in the constants of the output circuit, which causes the tuning thereof to vary slightly from the aforementioned approximation, has a slight though very definite effect upon the frequency of the oscillations generated.

In the modification of my invention illustrated in the drawing, the plate-filament paths of the shifter-tubes are included in a series circuit comprising a portion of the inductor 37, and the resistance of the combined plate-filament path is controlled at signal frequency by potentials placed on the grids of the tubes by the action of the microphone 35 and the transformer 33. When the current through the portion of the inductor 37 referred to is varied at signal-frequency, the effective reactance of the network including the entire inductor 37 is altered, and the frequency of the generated oscillations is 80 made to approach and recede from the mean, or normal, frequency at a rate and in an amount proportional to the energization of the microphone.

The direction and average amount of the 90 frequency-shift is controlled by properly adjusting the biasing potential applied to the grids of the shifter-tubes, with respect to the potential of the signal frequencies applied to the grids thereof.

The shift in frequency of the generated 95 oscillations is never very large, but is amply sufficient to impress signaling frequencies thereon. In one commercial embodiment of my invention, which has been in successful 100 operation over an extended period, the mean, or normal, oscillator frequency is 970 kilocycles and the shift obtained with voice modulation is of the order of 800 cycles.

The system of modulation I have disclosed herein is not restricted to crystal-controlled 105 oscillation-generators, but is also applicable to generators of other types, among which may be mentioned the well-known Hartley circuit, wherein the frequency is determined 110 by a tuned circuit, and capacitive or inductive means are employed for feed-back purposes. I have found that, if the inductor in the frequency-determining circuit is shunted by a network of the same character as that shown 115 in the drawing, a much larger frequency-shift may be obtained than if the oscillation 120 generator is of the crystal-controlled type, such shift being in some instances as large as 10,000 cycles away from the normal, or 125 mean, frequency.

The apparatus involved in the amplification and radiation of the shifting frequencies originating in the master oscillator differs 130 but slightly from similar apparatus utilized in radio systems of the types now familiar to those skilled in the art. It has been found beneficial in some instances, to slightly increase the decrement of the tuned coupling circuits employed between amplifier stages,

but there is no necessity for carefully biasing each thermionic amplifier device to the straight portion of its characteristic curve. Inasmuch as exact tuning of the coupling devices between the several amplifier stages is not found to be obligatory, the tendency toward self-oscillation in the several stages is noticeably absent.

- My invention is also of great value when it is desired to control a radio-transmitter from a remote point, inasmuch as all of the control energy required may be transmitted from a distant microphone over a pair of relatively small wires.
- Although illustrated as particularly adapted to the transmission of voice or analogous signals, my invention is by no means restricted thereto. Any appropriate means, such as a telegraph-key-controlled resistor, may be arranged in circuit with a portion of the impedance network associated with the output circuit of the oscillator tube, and the oscillation frequency may thereby be caused to vary abruptly between definite limits.
- Inasmuch as there is no appreciable time-lag between the excitation voltage and the shift in frequency, my invention is also particularly applicable to picture-transmission and television systems, wherein frequency-shifts of many thousands per second are necessary.

While I have shown and described only a single embodiment of my invention, it will be apparent to those skilled in the art that many modifications are possible. My invention, therefore, is not to be limited except insofar as is necessitated by the prior art and by the spirit of the appended claims.

I claim as my invention:

1. In an oscillation generator comprising a thermionic device having a tunable output circuit, a reactive network connected across said circuit, a circuit including a space discharge path conductively connected in shunt to a portion of said network, and means for varying the conductivity of said path, whereby the frequency of the generated oscillations may be controlled.
2. In an oscillation generator comprising a thermionic device having a tunable output circuit, a reactive network connected across said circuit, a circuit including a space discharge path conductively connected in shunt to a portion of said network, and vibration-responsive means for varying the conductivity of said path, whereby the frequency of the generated oscillations may be controlled by said vibration-responsive means.
3. In an oscillation generator comprising a thermionic device having a tunable output circuit, a reactive network connected across said circuit, a circuit including a space discharge path conductively connected in shunt to a portion of said network, a vibration-responsive device, a control-electrode in said

path, and means actuated by said vibration-responsive device for placing a variable electric charge on said control-electrode, whereby the conductivity of said path may be altered and the frequency of said generated oscillations controlled.

4. In combination with an electrical discharge device having an input circuit and an output circuit substantially without mutual induction, a piezo-electrical crystal means associated with said input circuit for determining approximately the frequency of oscillatory currents generated in said output circuit, tuning means for said output circuit, and signal-controlled means for varying said tuning for varying said frequency.

In testimony whereof, I have hereunto subscribed my name this 6th day of October, 1927.
